CLAIM

The ornamental design for a cable connector, as shown and described.

DESCRIPTION

FIG. 1 is a perspective view of a cable connector, showing the new design;

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof opposite that of FIG. 6;

FIG. 8 is a rear perspective view thereof;

FIG. 9 is an additional front perspective view thereof featuring a plate on which the cable connector is affixed; and,

FIG. 10 is an additional rear perspective view thereof featuring a plate on which the cable connector is affixed. The broken lines shown in the drawings represent portions of the cable connector that form no part of the claimed design

1 Claim, 7 Drawing Sheets
